Specification for Design.

Patented July 8, 1913.

Application filed August 12, 1912. Serial No. 714,753. Term of patent 7 years.

To all whom it may concern:

Be it known that I, VAN ZANDT M. MOORE, a citizen of the United States, residing at Cleveland, in the county of Cuyahoga and State of Ohio, have invented a new, original, and ornamental Design for Wheels, of which the following is a specification, reference being had to the accompanying drawing, forming part thereof.

In the drawings, Figures 1 and 2 are side

elevations of the wheel looking from opposite sides thereof; and Fig. 3 is a cross section on a diametric plane.

I claim:

The ornamental design for a wheel as shown.
